UNITED STATES PATENT OFFICE.

CLYDE S. PELTON, OF AKRON, OHIO.

COMBINED FOOT-REST AND HEATER.

1,102,432.

Specification of Letters Patent.

Patented July 7, 1914.

Application filed April 29, 1910. Serial No. 558,457.

To all whom it may concern:

Be it known that I, CLYDE S. PELTON, a citizen of the United States, residing at Akron, in the county of Summit and State of Ohio, have invented a certain new and useful Improvement in Combined Foot-Rests and Heaters, of which the following is a full, clear, and exact description, reference being had to the accompanying drawings.

My invention relates to heaters, and particularly to heaters of the combined register and radiator type which are employed for the purpose of utilizing the exhaust from the engines of motor vehicles for the purpose of heating such vehicles.

Certain features of the invention disclosed herein are designed with the view of providing a foot warmer for the occupants of the vehicle, with an arrangement where-by the supply of exhaust heating fluid may be conveniently controlled, and certain other features are designed with the view of making the heater reversible, for application to an exhaust pipe on either side of the vehicle.

The invention may be defined generally as consisting of the combinations of elements embodied in the claims hereto annexed and illustrated in the drawings forming a part hereof, wherein—

Figure 1 represents a rear elevation of a heater constructed in accordance with my invention; Fig. 2 a transverse sectional view through the heater shown in the preceding figure; Fig. 3 an end elevation of the heater, the support being shown in section; Fig. 4 a view corresponding with the line 4-4 of Fig. 2. Fig. 5 is a sectional detail of the valve controlling the supply to the heater; and Fig. 6 is a plan view showing the mode of attaching the heater to the exhaust pipe in direct and reversed position.

Describing by reference characters the various parts shown herein, 1 denotes the support for the heater, which may be the floor of an automobile; 2 denotes the exhaust pipe from the motor. This exhaust pipe will be connected with the engine and the exhaust from the engine will be presumed to flow through the pipe in the direction indicated by the arrow and, as the engine is generally located at the front of such vehicles, the terms "front" and "rear" will be applied correspondingly in connection with the drawings. This pipe passes through a pair of bearings comprising each a semi-circular clip 3 bolted to a base 4, said

base having a semi-circular seat formed therein for the adjacent portion of the supply pipe. The open side of the base is closed by a plate 5 which carries an elbow 6. This base supports a valve 60 having a projection 7 provided with a stem 8, said stem having an arm 9 connected thereto by means of which the valve may be rotated. The projection 7 extends about half way across the bore of the pipe 2 when the valve is in "open" position. The valve is of the type shown in my application of even date herewith #558,458 and requires no further detailed description herein. The arm 9 will be operated, by means to be set forth herein-after, to supply fluid to the heater, which will now be described.

The heater proper consists of a plurality of pipes 10 having their opposite ends connected to headers 11 and 12 respectively. The header 11 is provided with a threaded nipple 13, projecting through the floor 1 and having the elbow 14 connected thereto. The header 12 is provided at one end with a downwardly extending nipple 15 projecting through the floor 1 and having the elbow 16 threaded thereon, said elbow having a downwardly and rearwardly directed end 17 provided with a flared discharge outlet 18.

A casing 19 is applied to the vehicle bottom over the heater, said casing being provided with a bottom flange 20, by means of which it may be secured to the floor 1. The front of this casing is higher than the rear, and an inclined upper surface 21 extends from the rear to the front of the casing, the inclined surface being provided with openings 22 for the circulation of air, the air being supplied to the heater casing through the apertures 23 located just above the flange 20. The rear wall of the casing is provided with a slot 24 at the central portion thereof, said slot having notches 25 for the reception of a lever arm 26 which is provided at its outer end with an operating handle 27. The inner end of the arm 26 is connected to a vertical shaft 28 which extends through the floor and has at its lower end an arm 29 which is connected by a wire 30 with the end of the arm 9.

In operation, the occupant of the vehicle moves the handle 27 in the appropriate direction to rotate the valve in such direction as will uncover the inlet end of elbow 6 and cause the projection 7 to deflect part of the exhaust gases in the pipe 2 through elbow 6,

flexible pipe section 31 and elbow 14 into the heater. Owing to the arrangement of the headers and the connecting tubes and the discharge elbow 16, the gases are discharged 5 to the atmosphere without the production of any material noise, the heater and its discharge elbow forming in effect a muffler. By moving the handle in the opposite direction, the valve carrying the projection 7 will be 10 closed and the heater will be cut out. The notches 25 coöperate with the arm 26 to hold the valve in any intermediate position.

Among the advantages of my heater are 15 its extreme simplicity, which, however, does not detract from its efficiency; convenience of operation and its reversibility. If the exhaust pipe is on the right hand side of the vehicle instead of the left, it is necessary only to turn the heater end for end, locating 20 the apertures in the floor so as to receive the nipples 13 and 15 and turning the elbows 14 and 16 in the appropriate direction to extend respectively forwardly and rearwardly from their respective nipples.

25 Having thus described my invention, what I claim is:—

1. The combination, with a motor exhaust pipe, of a reversible heater having connections projecting from opposite ends thereof, a dis-

charge elbow reversibly connected with one 30 of said connections, a supply elbow projecting from the other connection and reversibly connected thereto, a connection between the supply pipe and the last mentioned elbow, the elbow connections permitting the heater 35 to be reversed for connection with the exhaust pipe on either side of the vehicle.

2. The combination, with the floor of a motor vehicle, of an exhaust pipe extending beneath said floor, a heater supported by 40 said floor and having connections projecting from opposite ends thereof, the lower ends at least of the connections being below said floor, a discharge elbow reversibly connected with one of said connections, a supply elbow 45 projecting from the other connection and reversibly connected thereto, a flexible connection between the exhaust pipe and the last mentioned elbow, the reversible elbows permitting the heater to be reversed for connection with the supply pipe on the other side of the vehicle.

In testimony whereof, I hereunto affix my signature in the presence of two witnesses.

CLYDE S. PELTON.
